(57) **CLAIM**

We claim the ornamental design for a latch handle for freezer, as shown and described.

DESCRIPTION

FIG. 1 is a front, top, and left side perspective view of a latch handle for freezer of the present invention;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view showing the handle part in a large scale thereof.

(Continued)

The broken lines shown are included for the purpose of illustrating the unclaimed portions of the freezer and form no part of the claimed design.
